COMBINED BESSEMER-OPEN HEARTH FURNACE

Lester D. Savage, Jr., Minneapolis, Minn.

Application January 24, 1952, Serial No. 268,028

6 Claims. (Cl. 266—35)

This invention relates generally to open hearth furnaces used in the process of reducing undesirable elements from iron such as pig iron prior to conversion of the iron into steel, and particularly concerns the heat source for such a furnace.

A common type of apparatus used to reduce the unwanted elements from iron in the steel making process is the open hearth furnace. This type of furnace has certain advantages over the Bessemer converter as are well known in the art. While the open hearth is slower operating than the Bessemer, it has a much greater capacity and the oxidation of elements is much more easily controlled. It is, however, necessary to provide a fuel supply, such as gas or oil, to the open hearth to keep a flame over the melt, a need which is undoubtedly more expensive than in the Bessemer to which only oxygen in some form need be supplied. With this in mind I have designed a furnace which is a combination Bessemer and open hearth and which retains the advantages of each.

The primary object of my invention is to provide an open hearth furnace with a new and improved heat source to materially reduce the expense of operation.

Another object of my invention is to provide an improved type of open hearth furnace having means for shortening the refining period.

Still another object of the invention is to provide an open hearth furnace having means for heating the lower portion of the melt to facilitate more rapid oxidation of the elements.

With these and other objects in mind, my invention broadly comprises the combining of a side blown Bessemer converter with a basic open hearth furnace in such a manner as to refine metal in both the Bessemer and furnace simultaneously and to utilize the exothermic heat created in the Bessemer to provide the flame over the melt in the furnace, and with the Bessemer and furnace so connected that the pure metal settling or circulating to the bottom of the melt in the Bessemer will flow into the lower portion of the melt in the furnace.

The above mentioned and still additional objects of the invention will be brought to light during the course of the following specification, reference being made to the accompanying drawing, in which—

Fig. 1 is a longitudinal vertical section of the improved portion of the furnace with directional arrows showing the direction of movement of the products of combustion and the melt.

Fig. 2 is a transverse horizontal section taken on line 2—2 of Fig. 1.

Fig. 3 is a transverse vertical section taken on line 3—3 of Fig. 1.

Referring now more particularly to the drawings, and using reference characters to designate like structural features, parts, and materials used in the different figures, the numeral 10 denotes generally a conventional open hearth furnace, only one side portion of which is shown in order that the important aspects of the invention might be clearly displayed in detail. The furnace has a bed or

2

liner 11 of basic refractory material and a roof 12 of acid liner connected by a peripheral side wall 13. This side wall has an acid exterior section and a basic interior section which run respectively into the roof 12 and bed 11 and which are separated by a zone of neutral refractory 14 leading from the interior surface of the wall to the center thereof and vertically downward therein isolating the basic and acid materials from one another. The furnace is adapted to be filled with molten metal M to a level at approximately the point on the side wall indicated by number 15, which lies below the uppermost boundary of the basic liner.

The Bessemer converter unit, designated generally at 16, is attached to the side wall of the furnace and may be used in connection with a conventional furnace having slight structural modifications made in the wall. The proper elevation of the converter with respect to the furnace may be observed in Fig. 1 and it will be noted that the converter in effect provides an auxiliary chamber to the furnace. The unit 16 has an acid liner forming a basin 17 at the bottom, with the top 18, end 19, and side walls 20 continuously curved in a bulbous shape to define a combustion chamber 21 over the basin. The top rim of the basin 17 is formed by a ridge 22 in the liner 16 extending on the horizontal around the basin to the wall 13 of the furnace. It will be noted that the bottom of the converter basin slopes downwardly toward the wall 13 and that the ridge 22, particularly at the outer end of the basin, extends outwardly over the bottom leaving the end wall of the basin 23 with a concave surface. A slag removal port 24 having a closure gate is provided in one of the walls 20 (Fig. 2).

The side wall 13 at the place of union with the converter is particularly constructed to allow the converter and furnace operation to be combined. An elongated tubular passage or duct 25 is provided through the wall to lie on a horizontal plane and substantially at right angles to the longitudinal alignment of the two units. This passage serves as a header for a series of downwardly angling tuyere forming outlets 26 arranged in parallel and equally spaced along the passage wall. The tuyere openings into the converter are at substantially the elevation of the basin rim formed by ridge 22 and the furnace melt level point 15. It is to be noted that the header passage is disposed substantially above the melt level line and that the tuyeres are disposed at an angle of from preferably five to fifteen degrees to the horizontal. An air compressor (not shown) for furnishing air or other oxygen containing gas under pressure to the passageway 25 is connected to the passageway by means of pipe 27. Immediately above the duct or passage 25, wall 13 is provided with a round port 28, the side walls 29 of which diametrically diverge toward the converter to align with and join the inwardly converging interior surfaces of the top 18 and side walls 20 of the converter combustion chamber 21, as shown in Figs. 1 and 2. Port 28 opens into both the interior of the furnace 10 and the converter chamber 21 at elevations above the normal melt line 15 of the furnace. Transversely wide slot-like openings 30 and 31 in the wall 13 connect the basin 17 with the furnace interior below the melt line (Figs. 1 and 3), opening 30 being disposed only slightly below tuyeres 26, and horizontally directed, while passage 31 extends between the bottoms of the two units and is diagonally directed, as shown in Fig. 1.

In operation of the apparatus, the open hearth furnace is charged in the normal manner with molten pig iron M, an amount of steel scrap being added thereto if desired, to the normal melt level line 15 of the furnace. Iron oxide may also be introduced into the melt if necessary and according to standard practices. As the melt is poured into the hearth a small portion thereof will obviously flow through passages 30 and 31 into the basin

of the converter. I find that it is preferable that the basin have a capacity in the range of from one to ten per cent of the furnace melt capacity. When the furnace is filled to the normal melt line 15 the melt level in the basin will come approximately to the mouths of the tuyeres, with the axes of the tuyeres at a slight angle to the surface of melt.

When the furnace has been fully charged, an aeriform oxygen agent, such as air under pressure, is allowed entrance to the passage 25 so as to blast out through the tuyeres 26 to commence the Bessemer process in the converter in a manner well known. The melt M lying in the basin 17 will be rapidly purified, the oxygen combining with and oxidizing the silicon, manganese, carbon and other elements remaining in the iron, forming acid slag S on the melt and filling the chamber 21 above the melt in the converter with the intense chemical heat of products of combustion. The blasts of oxygen containing agent issuing from the tuyeres pass across the surface of the melt allowing the oxygen to react therewith, and then tend to follow around the curved walls of the chamber to return toward their source and are guided through the port 28 and into the air space over the main body of melt M in the furnace. The heat thus furnished over the melt causes the carbon and other products in the melt to unite with the oxygen therein allowing the open hearth furnace to function in the normal manner.

Though intense exothermic heat is created by the mixture of carbon monoxide and oxygen in the chamber 21, this heat is even more greatly intensified by passage of the products of combustion into the furnace. This is due to the fact that in the rapid passage of the products through the port 28 the tapered walls 29 cause a further mixture of the carbon monoxide with the free oxygen carried therewith.

It will be obvious that as the upper strata of melt in basin 17 loses its silicon, carbon, etc., and becomes purified thereby it increases in weight per unit of volume and will settle to the bottom of the basin running downwardly along the slanted bottom thereof and through passage 31 into the bottom of the furnace. This action is accelerated by the oxygen blast from tuyeres 26 which directs the top wave of the melt against the wall 23, resulting in a continuous circulation of the melt in the basin from the upper to the lower strata in the direction indicated by the arrows. As purified melt leaves the converter basin through passage 31 it is continuously replaced by the more impure melt of the main body flowing into the basin through the passage 30. Slag accumulating in the converter may be removed through opening 24 after the oxygen supply to tube 27 has been temporarily cut off.

The advantages of my improvement on the open hearth furnace will be readily appreciated. By using the intense exothermic heat generated in the Bessemer as a medium for heating the main body of melt in the furnace in order that oxidation may take place, the expense of an external fuel is eliminated. Additionally the time period for complete refining is appreciably reduced. This is due to several factors: First, the reduction of elements takes place in both units. Secondly, the main mass of melt in the open hearth retains a more even temperature throughout, due to the fact that hot refined melt is continually being supplied through opening 31 to the lower portions of the mass. And, thirdly, as the hot products of combustion are blown through the port 28 they are forced into greater mixture with the excess oxygen traveling therewith causing further combustion of the carbon monoxide and increasing the exothermic heat over the main body of melt.

It is to be noted that the neutral liner 14 crosses the openings 30 and 31 preventing any wearing away of the opening walls by action of the basic and acid materials upon one another.

Of course both the furnace and converter may carry acid or basic liners or the Bessemer a basic and the open

hearth an acid if such is desirable. It is realized that use of the Bessemer process in combination with an open hearth furnace is not in itself novel. However, it is believed that a workable combination of the Bessemer converter with the furnace is heretofore unknown. The present invention makes possible the combined use of an acid Bessemer and a basic open hearth where a high silicon pig iron is the metal to be refined. Or, conversely, where the iron has a low silicon content so as to require an acid open hearth furnace or a basic Bessemer, my construction may be used for more efficient refining, as herein set forth.

It is also thought to be of no little importance that the oxygen supply can be controlled in such a manner as to slow the reduction toward the end of the refining period for termination at the proper time. When the oxygen blast is cut off there will necessarily be a backwash of the basin melt toward the tuyeres. However, the tuyere angle and the elevation of the header 25 prevent the melt from entering therein.

While herein I have continually referred to the converter as being mounted on the side wall of the furnace, it is to be understood that the term "side" is used relative to the top and bottom of the furnace and is inclusive of the side and end walls thereof. I have found it preferable to associate the converter with the furnace side wall at one end of the furnace and have so shown it in the drawings, although it will be appreciated that the invention can be carried out by mounting the converter on other than the end portion of the wall.

I have accordingly disclosed an improved metal refining furnace which efficiently and effectively carries out the aforementioned objectives. It is understood that suitable modifications may be made in the structure as disclosed, provided that such modifications come within the spirit and scope of the appended claims. Having now therefore fully illustrated and described my invention, what I claim to be new and desire to protect by United States Letters Patent is:

- 40 1. A furnace for the purification of metals having a bottom, a top and a continuous side wall defining a main melting chamber, a second furnace attached to the side wall of said first mentioned furnace and providing an auxiliary melting chamber, said side wall having a pair of vertically spaced horizontally directed passageways extending therethrough and connecting the two chambers whereby as the main melting chamber is charged to a level intermediate the two passageways the auxiliary chamber will be charged with melt to the same level, oxygen supply means having an outlet in said auxiliary chamber at a level intermediate said passageways for effecting the Bessemer process on the melt contained in said auxiliary chamber creating hot combustion gases thereover for escape through the upper passageway and into the main chamber, and said side wall having a third passageway below said pair of passageways and connecting the bottom of the auxiliary chamber to the main melting chamber for carrying purified melt from the auxiliary to the main chamber.
- 45 2. In an apparatus for refining iron or the like, an open hearth furnace having a continuous side wall enclosing a refining chamber and a heat source for said furnace comprising, a side blown enclosed Bessemer converter mounted on the side wall of the furnace, said converter having a melt receiving basin therein, the side wall having a passageway therethrough providing an open connection between the basin and the refining chamber of the furnace whereby the basin will receive a portion of a mass of metal melt introduced into the chamber, the side wall having formed therein a plurality of tuyeres disposed adjacent the top of the basin and directed toward the basin, means for supplying an oxygen containing gas to said tuyeres to blast against the top surface of melt in the basin to create hot combustion gases thereover, the side wall
- 50 3. In an apparatus for refining iron or the like, an open hearth furnace having a continuous side wall enclosing a refining chamber and a heat source for said furnace comprising, a side blown enclosed Bessemer converter mounted on the side wall of the furnace, said converter having a melt receiving basin therein, the side wall having a passageway therethrough providing an open connection between the basin and the refining chamber of the furnace whereby the basin will receive a portion of a mass of metal melt introduced into the chamber, the side wall having formed therein a plurality of tuyeres disposed adjacent the top of the basin and directed toward the basin, means for supplying an oxygen containing gas to said tuyeres to blast against the top surface of melt in the basin to create hot combustion gases thereover, the side wall
- 55 4. In an apparatus for refining iron or the like, an open hearth furnace having a continuous side wall enclosing a refining chamber and a heat source for said furnace comprising, a side blown enclosed Bessemer converter mounted on the side wall of the furnace, said converter having a melt receiving basin therein, the side wall having a passageway therethrough providing an open connection between the basin and the refining chamber of the furnace whereby the basin will receive a portion of a mass of metal melt introduced into the chamber, the side wall having formed therein a plurality of tuyeres disposed adjacent the top of the basin and directed toward the basin, means for supplying an oxygen containing gas to said tuyeres to blast against the top surface of melt in the basin to create hot combustion gases thereover, the side wall
- 60 5. In an apparatus for refining iron or the like, an open hearth furnace having a continuous side wall enclosing a refining chamber and a heat source for said furnace comprising, a side blown enclosed Bessemer converter mounted on the side wall of the furnace, said converter having a melt receiving basin therein, the side wall having a passageway therethrough providing an open connection between the basin and the refining chamber of the furnace whereby the basin will receive a portion of a mass of metal melt introduced into the chamber, the side wall having formed therein a plurality of tuyeres disposed adjacent the top of the basin and directed toward the basin, means for supplying an oxygen containing gas to said tuyeres to blast against the top surface of melt in the basin to create hot combustion gases thereover, the side wall
- 65 6. In an apparatus for refining iron or the like, an open hearth furnace having a continuous side wall enclosing a refining chamber and a heat source for said furnace comprising, a side blown enclosed Bessemer converter mounted on the side wall of the furnace, said converter having a melt receiving basin therein, the side wall having a passageway therethrough providing an open connection between the basin and the refining chamber of the furnace whereby the basin will receive a portion of a mass of metal melt introduced into the chamber, the side wall having formed therein a plurality of tuyeres disposed adjacent the top of the basin and directed toward the basin, means for supplying an oxygen containing gas to said tuyeres to blast against the top surface of melt in the basin to create hot combustion gases thereover, the side wall
- 70 7. In an apparatus for refining iron or the like, an open hearth furnace having a continuous side wall enclosing a refining chamber and a heat source for said furnace comprising, a side blown enclosed Bessemer converter mounted on the side wall of the furnace, said converter having a melt receiving basin therein, the side wall having a passageway therethrough providing an open connection between the basin and the refining chamber of the furnace whereby the basin will receive a portion of a mass of metal melt introduced into the chamber, the side wall having formed therein a plurality of tuyeres disposed adjacent the top of the basin and directed toward the basin, means for supplying an oxygen containing gas to said tuyeres to blast against the top surface of melt in the basin to create hot combustion gases thereover, the side wall
- 75 8. In an apparatus for refining iron or the like, an open hearth furnace having a continuous side wall enclosing a refining chamber and a heat source for said furnace comprising, a side blown enclosed Bessemer converter mounted on the side wall of the furnace, said converter having a melt receiving basin therein, the side wall having a passageway therethrough providing an open connection between the basin and the refining chamber of the furnace whereby the basin will receive a portion of a mass of metal melt introduced into the chamber, the side wall having formed therein a plurality of tuyeres disposed adjacent the top of the basin and directed toward the basin, means for supplying an oxygen containing gas to said tuyeres to blast against the top surface of melt in the basin to create hot combustion gases thereover, the side wall

interiors of the converter and furnace at an elevation above the converter basin, and the closure walls of the converter above the basin jointly forming a bulbous shaped interior surface converging to the port to direct the combustion gases through the port and into the chamber.

3. An apparatus for the purification of molten iron or the like comprising an open hearth furnace having a bottom, top and vertical side walls forming a main refining chamber, a second furnace having a bottom, top and side walls forming an auxiliary refining chamber and connected to a portion of the side wall of the open hearth furnace whereby said wall portion serves as a common vertical wall for both chambers, the bottom of said second furnace formed to provide a higher bottom for the second chamber than the bottom of the open hearth furnace provides for the main chamber, said common vertical wall having three vertically spaced passageways therethrough providing open connections between the two chambers, whereby when the main chamber is filled with a mass of molten metal to a level intermediate the uppermost and center passageway a portion thereof will flow into the auxiliary chamber filling it to the same level, means in said second furnace for blasting oxygen across the top of said melt portion in a direction away from the common wall to effect the Bessemer refining process thereon heating the melt portion and creating hot combustion gases in the second chamber over said melt portion, the lowermost passageway extending diagonally downward from the bottom of the auxiliary chamber to the main chamber for carrying purified melt thereto to heat the bottom portion of the mass, and the side and top walls of the second furnace having their interior surfaces forming a continuous bulbous shape whereby said gases under influence of the oxygen blast will follow therearound and back toward the common wall for passage through the uppermost passageway and into the main chamber to heat the main mass from above.

4. An apparatus of the character described comprising an open hearth furnace having a peripheral side wall defining a melting chamber within the furnace for holding a mass of metal melt, means for providing sufficient heat in the chamber over the melt mass for purifying the melt, and means for heating the lower strata of the mass which comprises a basin attached outside of and to the side wall of the furnace, said side wall having a pair of vertically spaced passageways providing open connection between the lower half of the chamber and the basin whereby a portion of the mass may flow into the basin, gas injection means for heating the melt portion in the basin, and means for circulating the melt in such a manner as to flow from the chamber to the basin through the upper passageway and from the basin to the chamber through the lower passageway.

5. An apparatus for the refining of pig iron or the like in a molten state comprising a pair of furnace each pro-

viding a melt refining chamber, said furnaces integrally connected and arranged in side by side relation with a common vertical wall separating the two chambers, means for introducing metal melt into each of the furnace chambers, means associated with one of said furnaces for effecting the Bessemer refining process on melt contained therein, means associated with the other of said furnaces for effecting the open hearth refining process on melt contained therein, one of said furnaces having a chamber liner of basic refractory material, the other of said furnaces having a chamber liner of acid refractory material, said common wall constructed to have an acid liner facing the acid lined furnace and a basic liner facing the basic liner furnace, said wall liners separated by a zone of neutral refractory material, said common wall having a pair of passageways therethrough for free flow of melt between the two chambers, and means for circulating the melt through the passageways.

6. An apparatus for the purification of molten iron or the like comprising an open hearth furnace having a bottom, top and vertical side walls forming a main refining chamber, a second furnace having a bottom, top and side walls forming an auxiliary refining chamber and connected to a portion of the side wall of the open hearth furnace whereby said wall portion serves as a common vertical wall for both chambers, said wall having at least two vertically spaced passageways therethrough providing open connections between the two chambers, whereby when the main chamber is filled with a mass of molten metal to a level above the entrance of the lowermost passageway to the auxiliary chamber a portion of the metal will flow into said auxiliary chamber filling it to the same level, means in said second furnace for blasting oxygen across the top of said metal portion in a direction away from the common wall to effect the Bessemer refining process thereon heating the melt portion and creating hot combustion gases in the second chamber over said metal portion, and the side and top walls of the second furnace having their interior surfaces forming a continuous bulbous shape whereby said gases under influence of the oxygen blast will follow therearound and back toward the common wall for passage through the uppermost passageway and into the main chamber to heat the mass from above.
